UNITED STATES PATENT OFFICE.

JOHN MELVIN JOHNSON, OF GALVA, KANSAS.

DOUBLE-PISTON GAS-ENGINE.

1,329,974.

Specification of Letters Patent.

Patented Feb. 3, 1920.

Application filed November 9, 1918. Serial No. 261,804.

To all whom it may concern:

Be it known that I, JOHN MELVIN JOHNSON, a citizen of the United States, residing at Galva, in the county of McPherson and 5 State of Kansas, have invented new and useful Improvements in Double-Piston Gas-Engines, of which the following is a specification.

The present invention comprehends generally improvements in that class of inventions known as internal combustion engines and more particularly has reference to a double piston gas engine.

The invention, as its primary object, aims 15 to provide an engine of the above mentioned character wherein there is employed two simultaneously movable pistons in a single cylinder while acting in conjunction and in timed relation with these parts is a rocking sleeve valve for controlling the admission and exhausting of gas to and from the cylinder thus providing an engine wherein maximum power and efficiency is obtained with the employment of a minimum amount 25 of fuel.

As an equally important object the present invention contemplates the provision of a device of the above mentioned character wherein a sleeve valve is mounted for rocking movement medially of the ends of the cylinder for controlling the admission and exhausting of gases to and from the cylinder while mounted on the power shaft and acting in conjunction with the sleeve valve is 30 a cam of improved construction for insuring of the actuation of the sleeve valve in timed relation with respect to the simultaneously removable pistons.

Among the other aims and objects of this 40 invention may be recited the provision of a device of the character described with a view to compactness, and in which the parts are few, the construction simple, the cost of production low and the efficiency high.

45 Other improvements and novel details in the construction and arrangement of the various parts of the apparatus will be brought out more in detail in the description to follow, which for a clear understanding of the 50 invention should be considered in connection with the accompanying drawings forming a part hereof, and wherein is disclosed for the purpose of illustration a convenient and satisfactory embodiment of the invention. It is to be noted in this connection that 55 minor changes in the construction and ar-

rangement of parts may be made without departing from the principle of operation of the various parts.

The invention is clearly illustrated in the 60 accompanying drawings, in which:

Figure 1 is a side elevation of the improved engine.

Fig. 2 is a top plan view thereof.

Fig. 3 is a longitudinal central sectional 65 view of the invention.

Fig. 4 is a transverse section taken on line 4—4 of Fig. 2.

Fig. 5 is a transverse sectional view of the same part shown in another position. 70

Fig. 6 is a perspective detail of the sleeve valve.

Fig. 7 is a plan diagram of the cam.

Similar characters of reference are employed in all of the above described views, 75 to indicate corresponding parts.

Referring now, more particularly, to the accompanying drawings there is provided a single cylinder 1 supported by suitable legs 2 which are in turn secured to the floor by 80 the fasteners 3. Extending from diametrically opposite points and from the respective ends of the cylinder 1 are spaced parallel arms 4 which terminate in bearings 5 in which bearings are journaled shafts 6 85 formed in turn with crank portions 7 positioned between the arms 4. Pistons 8 and 9 are slidably mounted in the cylinder and are disposed to face each other while operatively connected to the piston heads are 90 rods 10 the outer ends of which are looped as at 11 and are arranged in engagement with the crank portions 7 of the shafts 6. These shafts 6 are further supported in vertical bearing standards 12. 95

A power shaft 13 is now employed and is journaled in bearing standards 14 which are connected to the floor as at 15. A relatively large gear wheel 16 is mounted on the power shaft and meshes with other large 100 gear wheels 17 in turn carried by the adjacent ends of the shafts 6 for transmitting rotary motion from the shaft 6 to the power shaft 13. A power or pulley wheel 18 is connected to one end of the power shaft 13. 105

In order to control the admission and exhausting of gases to and from the cylinder 1 a sleeve valve generally indicated by the numeral 19 is employed being preferably of a split type while carried by the outer 110 surface of the sleeve valve at a point opposite the split is an arcuate bar 20 from

which projects a lug 21 at a point medially of the ends of the bar. This sleeve valve is rockably mounted transversely and medially of the ends of the cylinder 1 the 5 inner bore of the cylinder being formed near its upper portion with an arcuate groove 22 in which is fitted for sliding movement the arcuate bar 20, the groove being longer than the bar to permit of rocking 10 movement of the valve. The cylinder is also formed medially of the ends of the groove with the slot 23 in which operates the lug 21. On opposite sides of the sleeve valve the inner bore is provided with annular grooves 24 in which are fitted guide 15 rings 26. The sleeve valve is further provided with diametrically opposed inlet openings 27 and diametrically opposed exhaust openings 29 which, on rocking movement of 20 the sleeve valve, are adapted to respectively and alternately align or register with the branch pipes 28 of the inlet manifold and with the branch pipes 30 of the exhaust manifold 31. In insuring of the sleeve 25 valve 19 being rocked in timed relation with respect to the actuation of the simultaneously movable piston heads 8 and 9 a cam wheel 32 is rigidly connected to one end of the supplemental shaft 30' which 30 is journaled in the bearing standard 31' and carries on its inner end a gear 32' which meshes with a cog wheel 33' carried on the adjacent end of the power shaft and by this arrangement it is to be appreciated 35 that the intermeshing gears serve as a means for transmitting motion at the proper rate of speed from the shaft 13 to the shaft 30'. A wheel 32 is positioned directly above the center of the cylinder and formed in its 40 periphery with a sinuous groove 33 clearly illustrated in Fig. 7. By referring to this figure it is to be appreciated that the groove 33 has one half of its circumference straight as indicated by the numeral 34 while the 45 other half is zigzag as at 35 and 36 in opposite directions. By this arrangement it is to be appreciated that during rotation of the power shaft 13 the cam wheel will be rotated and inasmuch as the lug 21 50 operates in the groove 33 the sleeve valve will be shifted. For instance, assuming that the lug is moved to one side by its engagement with the zigzagged portion 36 of the groove then the exhaust openings 27 will be 55 registered with the branch pipes 30 of the exhaust and simultaneous with this action the pistons 8 and 9 assume a sliding movement toward each other on their exhaust stroke for the forcing of the burnt gases 60 through the exhaust openings 27 and the exhaust branch pipe 30. A continued rotary motion causes the valve to be rocked to the other side for the registering of the inlet openings 26 with the branches 28 of the 65 inlet manifold 31 for the admission of fresh

gases which are drawn thereinto on the intake stroke of the pistons as they move away from each other toward the outer ends of the cylinder. Immediately after this arrangement of parts the lug is engaged by 70 the straight portion 34 of the groove and is kept from rocking movement during the compression and firing strokes of the piston heads 8 and 9 and immediately after the firing stroke the exhaust stroke occurs 75 as above set forth and this cycle of operation is repeated. It is to be appreciated, of course, that a spark plug 37 is employed for the firing of the gases at the proper time. 80

It is believed in view of the foregoing description that a further detailed description of the operation of the invention is entirely unnecessary. Likewise it is believed that the advantages of the invention will 85 be readily apparent.

As many changes could be made in the above construction and many apparently widely different embodiments of this invention could be made without departing from 90 the scope thereof it is intended that all matter contained in the above description or shown in the accompanying drawings shall be interpreted as illustrative and not in a limited sense. It is also to be understood 95 that the language used in the following claims is intended to cover all the generic and specific features of the invention herein described and all statements of the scope of the invention which as a matter of language might be said to fall therebetween. 100

What is claimed is:

1. An engine of the character described including a cylinder, pistons operating 105 therein, a power shaft, transmission mechanism between the pistons and power shaft, a sleeve valve rockably mounted medially the ends of the cylinder, a lug projecting from the sleeve valve, a rotatably mounted cam operably connected to the power shaft, 110 and provided in its outer periphery with a sinuous groove in which is engaged the lug to insure of the rocking of the sleeve valve in timed relation with the actuation of the pistons. 115

2. An engine of the character described including a cylinder, inlet and exhaust pipes communicating therewith, piston heads operating in the cylinder, a power shaft, transmission means operably mounted between the piston heads and the power shaft for transmitting motion thereto, a sleeve valve rockably mounted in the cylinder medially of the ends thereof and provided with inlet and exhaust openings for registration at times with the inlet and exhaust pipes, a lug carried by the sleeve and projecting exteriorly of the cylinder, a supplemental shaft geared with the power shaft, and a cam wheel on the supplemental shaft 120 125 130

and having a sinuous groove in its outer periphery for engagement about the lug for rocking the sleeve valve in timed relation with the actuation of the pistons.

- 5 3. An engine of the character described including a cylinder, inlet and exhaust pipes communicating therewith at points medially of the ends thereof, pistons operating in the cylinder, rotatably mounted crank shafts, 10 piston rods operably arranged between the piston and the crank shafts, a rotatably mounted power shaft, a gear on the power shaft, gears carried by the crank shaft and meshing with the power shaft for assuring 15 of the simultaneous actuation of the pistons and for the transmission of movement to the power shaft, a sleeve valve rockably mounted in the cylinder medially of the

ends thereof, means for guiding the rocking movement of the valve, a lug carried by the 20 valve and projecting through the cylinder, the valve being provided with inlet and exhaust openings for registration at times with the inlet and exhaust pipes, a rotatably mounted supplemental shaft, transmission 25 means between the supplemental shaft and the power shaft, a cam wheel carried by the supplemental shaft and positioned above the cylinder and having a sinuous groove in its outer periphery for engagement about 30 the lug for assuring of the rocking of the valve in timed relation with respect to the operation of the pistons for controlling the admission and the exhausting of gases.

In testimony whereof I affix my signature. 35
J. MELVIN JOHNSON.
